UNITED STATES PATENT OFFICE.

BERT E. HADLEY, OF LOS ANGELES, CALIFORNIA.

GAS MAKER AND COMBUSTION APPARATUS.

1,300,230.

Specification of Letters Patent.

Patented Apr. 8, 1919.

Application filed November 27, 1918. Serial No. 284,438.

To all whom it may concern:

Be it known that I, BERT E. HADLEY, a citizen of the United States, residing at Los Angeles, in the county of Los Angeles and 5 State of California, have invented new and useful Improvements in Gas Maker and Combustion Apparatus, of which the following is a specification.

This invention relates to improvements 10 in a gas maker and combustion apparatus for stoves, furnaces, fireplaces, and the like, and particularly pertains to that type thereof in which a hydrocarbon fuel is delivered to a retort and discharged therefrom in the 15 form of vapors through a conduit leading from the retort in such manner that on ignition flames will be directed against the retort to maintain a generating action.

It is the object of this invention to provide 20 a device of the above character in which substantially complete or perfect circulation of the fluid fuel may be maintained through the retort and conduit to reduce the formation of carbon deposits in the apparatus 25 and especially in the conduit, and also to provide means for collecting such carbon deposits and heavy residue as may accumulate in the device and thereby reduce the possibility of clogging of the burner or 30 discharge orifice to a minimum.

Another object is to provide means for 35 radiating heat throughout the interior of the apparatus to effect a thorough and rapid vaporization of the hydrocarbon fuel by 40 which the device is rendered particularly serviceable in burning the heavier hydrocarbons and especially kerosene.

A further object is to provide a construction 45 whereby oxidizing of the discharge orifice and the resultant clogging thereof will be largely obviated embodying means whereby the flames will not be formed directly at the margin of the discharge orifice but at a point slightly remote therefrom.

Further objects will appear hereinafter.

The invention is illustrated in the accompanying drawings, in which;

Figure 1 is a perspective view of the apparatus.

Fig. 2 is a view of same as seen in vertical section.

Fig. 3 is a plan view and section on a reduced scale as seen on the line 3—3 of Fig. 2 with parts broken away.

More specifically 5 indicates a bowl-shaped container forming a retort to the interior of

which hydrocarbon fuel is delivered either by gravity flow or under pressure through a feed pipe 6 connecting preferably with the lower portion of the retort and leading from 60 any suitable source of supply through a control valve not here shown.

The retort is entirely inclosed and has a top wall 7 the upper face of which is tapered upwardly from its edges toward its center to 65 form a slightly conical flame deflecting surface 8 and against which flames are impinged as will later appear to heat the contents of the retort. As a means for rapidly and effectively radiating heat throughout the 70 interior of the retort a series of dependent heat radiants 9 are formed on the under side of the top wall and extend to within a short distance of the side and bottom walls of the retort.

A conduit 10 leads upwardly from the upper portion of the retort and opens to the interior thereof preferably through the top wall adjacent to its outer edge. This conduit is arched over the top wall and spaced 80 therefrom and is turned downwardly at the opposite side of the retort with its other terminus opening to the interior of the retort adjacent to the bottom portion thereof to afford a means for substantially perfect 85 circulation of the fluid fuel. At a point centrally of the arched portion of the conduit a recess 11 is formed on its under side by a conical wall 12 extending upwardly into the interior of the conduit. The upper or apex 90 portion of the conical wall terminates in spaced relation to the upper wall of the conduit and formed in its apex is a downwardly opening discharge orifice 13 through which the fluid fuel may be directed toward the 95 top wall of the retort. The discharge orifice is thus arranged above the bottom wall of the conduit and is thereby less liable to become clogged by accumulations of carbon or sediment in the conduit. The discharge 100 orifice being recessed prevents combustion taking place immediately at the mouth of the orifice because sufficient air to support combustion can not mix with the vapors discharged from the orifice until the vapors 105 are projected beyond the rim of said recess. This prevents oxidization of the metal at the mouth of the orifice to a large degree. A plug 14 is screwed in the upper wall of the conduit directly over the conical wall and 110 provides means of access to the interior of the conduit for cleaning purposes.

Formed in the lower portion of the intake end of the conduit is a series of baffles 15 and 16 arranged in staggered relation on the outer and inner portions of the conduit 5 walls respectively serving as deflectors; the inner set of baffles also acting as heat radiants to further heat the vapors on entering the conduit. Arranged on the bottom wall of the arched portion of the conduit is a 10 series of upturned riffles 17 disposed between the baffles and the conical wall 12, the riffles gradually increasing in height progressively from the lowermost riffle to the uppermost to position the tips of the riffles in 15 different stratas of the vapors passed thereto to more effectively heat the vapors. A series of pockets are formed between the riffles which serve to catch and collect such particles of carbon and residue as are carried into the conduit and which gravitate to the bottom of the latter, the riffles thus 20 preventing particles of carbon from being carried to the discharge orifice. As the accumulation of carbon and residue 25 tends to be greatest at the uppermost portion of the conduit an enlarged pocket 18 is formed at the base of the conical wall 12 and the conical wall is extended thereabove such distance that carbon particles tending 30 to pass to the discharge orifice will be deflected and caused to fall into the pocket at its base.

The inner walls of the conduit are thickened at their intersection with the top wall 35 as indicated at 19 to provide an increased wall thickness at the point where the conduit is most subjected to the action of flames. This increased wall thickness is tapered from its inner edge to deflect flames 40 directed thereagainst.

A generating pan is formed on the lower portion of the retort and consists of an annular channel encircling the retort to receive alcohol or other heating elements 45 which on being ignited serves to initially generate vapors in the retort.

In the operation of the invention the liquid fuel is delivered to the retort and the latter subjected to such heat as to effect initial generation of a portion of the fuel into vapors which pass upward through the intake end of the conduit as indicated by the arrow *a* filling the conduit throughout. A portion of this volume of vapors is 50 charged through the orifice 13 under the pressure set up in the retort and after mixing with air are ignited, the flames being projected downwardly upon the flame spreading surface of the retort top wall and 55 thereby highly heating the latter and the dependent radiants so as to continue the generating action. The discharge orifice is spaced such distance from the retort that the vapors discharged therethrough will be 60 thoroughly mixed with air to form a highly 65

combustible mixture which on being ignited burns with an intensely hot flame.

Within the retort the vapors immediately beneath the top wall and in the intake portion of the conduit will be heated to a higher 70 temperature than those in the lower portion of the retort at the return end of the conduit, the vapors in this portion of the conduit being slightly cooled will fall and pass back into the retort to displace the hot vapors rising in the conduit, as indicated by the arrow *b*. This causes a substantially perfect continued circulation through the conduit of such portions of the vapors as are not discharged through the orifice 13. 80 This circulation is insured by reason of the intake end of the conduit being positioned above the return end thereof and because of the vapors being heated at the intake end of the conduit to a temperature higher than 85 that at the return end, and is important in that the formation of carbon in the conduit is reduced to a minimum and such carbon as is formed is prevented from clogging or choking the conduit. As the major portion 90 of such carbon as is formed and deposited in the apparatus takes place in the intake portion of the conduit it is collected in the riffles from which it is removed through the 95 plugged opening at the upper end of the conduit as occasion may require.

Continuous circulation of the vapors is further facilitated by reason of the intake end of the conduit being restricted by the baffles, which also serve as radiants to 100 maintain the vapors entering the conduit at a higher temperature than those returning into the retort.

While I have shown and described a specific embodiment of my invention it is obvious that the various details of construction are subject to modification and such may be resorted to without departing from the spirit and scope of the invention as set forth in the appended claims.

I claim:

1. In a gas maker and combustion apparatus, a retort, a conduit connected at one end to the upper portion of said retort and at its other end to the lower portion of the 115 retort with the intermediate portion of said conduit extending over the retort and spaced therefrom, said intermediate portion of said conduit being formed with a downwardly opening discharge orifice, and means for delivering liquid fuel to the interior of said retort.

2. In a gas maker and combustion apparatus, a retort, an arched conduit connected at its ends to said retort and extending 125 thereover, said conduit formed with a discharge orifice opening toward said retort, and a series of carbon traps formed in said conduit between one of its ends and said discharge orifice.

3. In a gas maker and combustion apparatus, a retort, an arched conduit connected at its ends to said retort and extending over the latter having a discharge orifice on its under side opening toward said retort, a series of baffles in said conduit, and a series of carbon collecting riffles formed in said conduit between said baffles and the discharge orifice.
- 10 4. In a gas maker and combustion apparatus, a retort having a top wall, a series of heat radiants on the under side of said top wall, and a conduit connected at one end to the upper portion of said retort and at its 15 other end to the lower portion of said retort whereby a circulation of vapors may be effected throughout the interior of said retort and around said radiants.
5. A gas maker and combustion apparatus 20 comprising a retort having a top wall, a flame spreader on the top wall, heat radiants depending from the under side of the top wall, and a conduit connecting at one end to the upper portion of said retort extending over and spaced from the top wall and flame 25 spreader and connected at its opposite end to the lower portion of said retort, said conduit formed with a recessed discharge orifice opening downward toward said flame spreader.
- 30 6. A gas maker and combustion apparatus comprising a retort having a top wall forming a flame spreader, heat radiants depending from the under side of said top wall into the interior of said retort, a conduit connected at one end to the upper portion of said retort and extending thereover with its other end connected to the lower portion of said retort, said conduit formed with a recessed discharge orifice on its under side, 35 carbon collecting riffles in said conduit adjacent to said discharge orifice, and baffles extending into said conduit forming deflectors and heat radiants.

BERT E. HADLEY.
